(57) **CLAIM**

We claim the ornamental design for an ergonomic medical catheter control handle, as shown and described.

DESCRIPTION

FIG. 1 illustrates a frontal perspective view of an ergonomic medical catheter control handle showing our new design; FIG. 2 illustrates a rear perspective view of our design; FIG. 3 illustrates a top down plan view of our embodiment; FIG. 4 illustrates right side plan view of our embodiment; FIG. 5 illustrates a bottom plan view of our embodiment; FIG. 6 illustrates a front plan view closest to control button of the handle of our embodiment; and, FIG. 7 illustrates a rear plan view (from a point distal to the control button) of the handle of our embodiment. The features shown in broken lines in various Figures are for illustrating reference or environmental structure and form no part of the claimed design.
